UNITED STATES PATENT OFFICE.

FRANK BODINE, OF RICHHWOOD, MINNESOTA.

ROAD-SCRAPER.

1,212,008.

Specification of Letters Patent.

Patented Jan. 9, 1917.

Application filed May 31, 1916. Serial No. 100,865.

To all whom it may concern:

Be it known that I, FRANK BODINE, a citizen of the United States, residing at Richwood, in the county of Becker and 5 State of Minnesota, have invented new and useful Improvements in Road-Scrapers, of which the following is a specification.

The invention relates to a road grader or leveler designed with a view to providing a 10 wheeled implement which may be readily transported to the place of use in comparatively compact form, and which in use may be adjusted to secure the desired result.

The improved road grader comprises a 15 main beam in the form of a wheeled truck, to which the leveling beams are connected in a manner to permit their adjustment for various purposes.

The invention in the preferred form of de- 20 tails will be described in the following specification, reference being had particularly to the accompanying drawings, in which:—

Figure 1 is a plan view of the improved road grader; Fig. 2 is a side elevation of the 25 same; Fig. 3 is a front elevation with the draft attachment omitted; Fig. 4 is a plan showing the leveling means in the inoperative position.

Referring particularly to the accompany- 30 ing drawings, the improved road leveler or grader comprises a main beam 1, of appropriate length, mounted at the respective ends upon ground wheels 2 and 3.

Combined with the main beam 1, are what 35 I term leveling beams 4 and 5. These beams are of duplicate construction and each include a beam like element on the relatively inner side and at the forward end is arranged a scraper or cutting blade 6. The 40 blade is secured to the edge of the beam and is of concavo-convex formation in vertical section in order to provide for a rolling or spreading of the material collected by the scraper. The leveling beams are mounted at 45 their rear ends to the main beam by flexible connectors, such as chains 7, and the connection between the chains, which are fixed to the main beam and the leveling beams, is such that the length of the chains between 50 the main beam and leveling beams may be transferred at will, for a purpose which will later appear.

Each leveling beam is provided with a 55 bar 8 secured to the upper surface thereof, and projecting inwardly therefrom, the stay

bar being connected to the main beam by a flexible connector 9. The leveling beams are each also provided with an upright post 10, which through the medium of a chain 11 is connected to the chain 9, the main beam 60 terminals of the chains 9 and 11, being arranged for adjustable connection so that the length of the chains may be transferred at will.

The main beam is provided with a cross 65 strut 12, of a length to permit the disposition of the forward ends of the leveling beams thereon, uprights 13 being secured at the ends of the strut to prevent lateral displacement of the leveling beams when in 70 place. The main beam is also provided with a hook or other clevis connection for the attachment of the draft animals, and at the rear end is provided a seat 14 for the operator.

In use, it will be obvious that through the 75 medium of the chains 9, the forward ends of the leveling beams may be spread to the desired extent, that is, in accordance with the width of the road or that width of the 80 road desired to level or scrape. By varying the inclination of the scraper blade 6, through the adjustment of the chains 11, the cutting depth or scraping depth of said 85 blades may be adjusted in accordance with requirements. Furthermore, as the beams 4 and 5 tend to level the material directed inward by the blades 6, it is obvious that the desired width of "crown" of the road may be controlled by the adjustment of the 90 chains 7. Of course, in transport from place to place the leveling means are supported upon the main beam and upon the strut 12.

Having described my invention, what I 95 desire to secure by Letters Patent is:—

A road scraper including a main beam, leveling beams arranged on opposite sides thereof, adjustable chain connections between the rear ends of the leveling beams and the main beam, chains secured to the 100 leveling beams and adjustably secured to the main beam to vary the distance of the forward ends of the leveling beams from the main beam at will, rods rising vertically from the leveling beams, and chains connected to the upper ends of said rods with the first mentioned chains to provide for 105 tilting the leveling beams.

In testimony whereof I affix my signature.
FRANK BODINE.
